(57) CLAIM

The ornamental design for the external surface configuration for the front panel of an over the range microwave oven, as shown and described.

DESCRIPTION

FIG. 1 is a front perspective view of an external surface configuration for the front panel of an over the range microwave oven showing our new design;

FIG. 2 is a front perspective view thereof, with the door in an open position;

FIG. 3 is a top plan view thereof;

FIG. 4 is a left side elevation view thereof;

FIG. 5 is a front elevation view thereof;

FIG. 6 is a right side elevation view thereof; and,

FIG. 7 is a bottom plan view thereof.

The details shown in broken lines in all views and the undisclosed rear view form no part of the claimed design.
